UNITED STATES PATENT OFFICE.

WELTON H. ROZIER AND SAMUEL C. IGOU, OF ST. LOUIS, MISSOURI.

STARTING DEVICE FOR INTERNAL-COMBUSTION ENGINES.

No. 927,681.

Specification of Letters Patent.

Patented July 13, 1909.

Application filed October 10, 1908. Serial No. 457,052.

To all whom it may concern:

Be it known that we, WELTON H. ROZIER and SAMUEL C. IGOU, citizens of the United States, residing at St. Louis, in the State of Missouri, have invented a certain new and useful Starting Device for Internal-Combustion Engines, of which the following is such a full, clear, and exact description as will enable any one skilled in the art to which it appertains to make and use the same, reference being had to the accompanying drawings, forming part of this specification.

Our invention relates to improvements in starting devices for internal combustion engines, and more particularly to that form of starting device shown and described in our prior application No. 442,837, filed July 10, 1908.

The object of our invention is to provide means whereby the electrical generator may be allowed to return to its initial position independently of the actuating connections, and further to provide means whereby the actuating connections are automatically locked against movement so as to prevent the accidental engagement of the connections with the generator while the generator is in motion.

In the accompanying drawings, which illustrate some forms of starting devices made in accordance with our invention, Figure 1 is a sectional view, Fig. 2 is an enlarged side elevation showing a slight modification, Fig. 3 is a view similar to Fig. 2 but showing a still further modification, Fig. 4 is a top plan view showing the form of device illustrated in Fig. 3, Figs. 5, 6 and 7 are enlarged views showing details of construction, Fig. 8 is a side elevation of the generator and operating connections therefor, Fig. 9 is a section through the gearing shown in Fig. 8 and Figs. 10 and 11 are detailed views of the parts of the gearing shown in Fig. 9.

Like marks of reference refer to similar parts in the several views of the drawings.

10 represents a magneto electric machine which is driven from an internal combustion engine 11 through the interposition of a device 12 adapted to allow a limited relative movement between the engine and the magneto, as will be hereinafter more fully described. The engine 11 and magneto 10 are mounted upon the frame 13 of a motor vehicle. The device 12 is provided with a toothed gear 14 which is adapted to be en-

gaged by a rack 15. This rack 15 moves in a guide 16 mounted on the crank shaft casing 17 of the engine 11. The end of the rack 15 engages with a slot 18 in an arm 19 pivotally mounted on a bracket 20 also secured to the crank shaft casing 17. A spring 21 normally holds the arm 19 in the position shown in Fig. 1. Passing through a slot 22 in the arm 19 is a bar 23 provided with a notch 24 adapted to engage with a pin 25 passing through the said arm 19. The end of the bar 23 is pivoted at 26 to a suspension link 27 and also to a stem 28 carrying a foot piece or pedal 29 by means of which the suspension link 27 may be moved on its pivot 30 to force the bar 23 forwardly and thus actuate the arm 19. The pivot 30 of the link 27 is provided with a spring 31 for returning it to its normal position. The forward end of the bar 23 is provided with an inclined face 32 adapted to strike on a roller 33 carried by an extension 34 on the bracket 20 when the bar 23 has neared its forward limit of movement, the result of which will be to lift the bar 23 so as to disengage the notch 24 from the pin 25 and release the arm 19 so that the magneto may return to its initial position in relation to the engine and thus produce the initial or starting spark for the engine.

In order to prevent the accidental actuation of the pedal 29, the stem 28 is provided with a pin 36 adapted to pass through a cross-slot 37 formed near the upper end of a slot 38 in which the stem 28 works. Guide pieces 39 are carried on the inner face of the plate 40 containing slots 37 and 38 so as to guide the pin into a position to pass through the cross-slot 37 when the pedal is returning to the normal position. Its weight then causes it to fall down to the position shown in Fig. 5 of the drawings and, consequently, the pedal cannot be operated until it is lifted sufficiently to bring the pin 36 into alignment with the slot 37. This prevents the accidental actuation of the pedal 29 while the machine is in operation. This might otherwise occur and cause either the breakage of the connections or of the generator itself.

In Fig. 2 I have shown a slight modification in which a toothed segment 45 is substituted for the rack 15. This toothed segment 45 engages with the wheel 14 and is carried by a bracket 46 supported on the crank shaft casing 17. An arm 47 for actuating

the segment 45 is connected by means of a link 48 with the end of the arm 19. In this construction the slot 18 may be omitted from the arm 19. The operation of this 5 form of starting device is so similar to that above described that it need not be given in detail.

A still further modification is shown in Figs. 3 and 4 of the drawings. In this modification the wheel 14 is adapted to be engaged by a pinion 50 carried by a bifurcated arm 51 shown in detail in Fig. 7. This arm 51 is supported on the crank shaft casing 17 by means of a bracket 52. The pinion 51 is 15 provided with a drum 53 upon which is wound a cord 54. This cord 54 passes around pulleys 55, 56 and 57 and is secured to the end of the arm 19 hereinbefore described. Within the drum 53 is a coil spring 20 58 which is secured at one end to the said drum and at the other to the arm 51 so as to rotate the drum in the direction to coil the cord 54 thereon. The arm 51 is also provided with a spring 60 which spring is some- 25 what lighter than the spring 58 so that when the cord is actuated by the movement of the arm 19 the arm 51 will first be swung on its pivot before the pinion 50 is rotated. As soon, however, as the pinion 50 comes into 30 engagement with the wheel 14, the movement of the arm 51 will be stopped and the further movement of the cord 54 will rotate the pinion and thus actuate the wheel 14. As soon as the arm 19 is released by the 35 engagement of the inclined face 32 of the bar 23 with the roller 33, the pinion 50 will move out of engagement with the wheel 14.

The particular form of connection for allowing a limited movement between the engine and generator, while in itself not forming a part of the present invention, is necessary to a proper understanding thereof and will now be described. Rigidly mounted on the end of the armature shaft 61 of the magneto 10 is the toothed disk 14. The disk 14 is provided with a hub 62 on which is loosely mounted the beveled gear wheel 12. The beveled gear wheel 12 is provided with a sleeve 63 fitting over the hub 62 as best shown in Fig. 9. The disk 14 and beveled gear wheel 12 are recessed on their opposing faces so as to form a chamber 64 adapted to receive the coil spring 65. This coil spring 65 is attached at one end by means of a pin 55 66 to the sleeve 63 on the beveled gear wheel 12 and at the other by means of a pin 67 to the toothed disk 14. The beveled gear wheel 12 is provided with a cut-away portion 68 preferably extending about half way 60 around its circumference. This cut-away portion 68 is adapted to receive a lug 69 formed on the toothed disk 14. This allows of a limited movement between the disk 14 and the beveled gear wheel 12 and at the 65 same time these two parts are normally held

together by means of the tension of the coil spring 65 so that the lug 69 is retained in the position shown in Fig. 8 of the drawings. In order to permanently lock these parts together in case the spring 65 should become 70 broken or weakened, I provide a hole 70 formed partly in the lug and partly in the adjacent part of the wheel 12 so that by the insertion of a screw or pin the parts may be firmly locked together. The beveled gear 75 wheel 12 meshes with a beveled gear wheel 71 carried on an upright shaft 72 connecting the crank shaft (not shown) of the engine with the shaft which drives the valve gear of the engine.

It will be evident that the above construction allows the armature of the generator to be moved independently of the engine and that the spring 65 will return the armature to its initial position to give a 85 starting spark.

Having fully described our invention, what we claim as new and desire to secure by Letters Patent of the United States is:

1. The combination with an internal combustion engine, of an electrical generator therefor, gearing for driving said generator, means for permitting a limited movement of said generator relative to said engine, actuating means adapted to be moved into and out of engagement with said generator, an operating device for said actuating means, and a tripping device interposed between said actuating means and operating device to disengage them while said actuating means is in engagement with said generator. 90

2. The combination with an internal combustion engine, of an electrical generator therefor, gearing for driving said generator from said engine, means for permitting a limited movement of said generator relative to said engine, actuating means adapted to be moved into and out of engagement with said generator, an operating device for said actuating means, and an automatic tripping device interposed between said actuating means and operating device to disengage them while said actuating means is in engagement with said generator. 105

3. The combination with an internal combustion engine, of an electrical generator therefor, gearing for driving said generator from said engine, means for permitting a limited movement of said generator relative to said engine, actuating means adapted to be moved into and out of engagement with said generator, an operating device for said actuating means, a tripping device interposed between said actuating means and operating device for disengaging them while said actuating means is in engagement with said generator, and means for locking said operating device against movement. 115

4. The combination with an internal combustion engine, of an electrical generator 120

therefor, gearing for driving said generator from said engine, means for permitting a limited movement of said generator relative to said engine, actuating means adapted to be moved into and out of engagement with said engine, an operating device for said actuating means, an automatic tripping device interposed between said actuating means and operating device for disengaging them while said actuating means is in engagement with said generator, and means for locking said operating device against movement.

5. The combination with an internal combustion engine, of an electrical generator therefor, gearing for driving said generator from said engine, means for permitting a limited movement of said generator relative to said engine, actuating means adapted to be moved into and out of engagement with said generator, an operating device for said actuating means, a tripping device interposed between said actuating means and operating device for disengaging them while 10 said actuating means is in engagement with said generator, and automatic means nor-

mally locking said operating device against movement.

6. The combination with an internal combustion engine, of an electrical generator 30 therefor, gearing for driving said generator from said engine, means for permitting a limited movement of said generator relative to said engine, actuating means adapted to be moved into and out of engagement with 35 said generator, an operating device for said actuating means, an automatic tripping device interposed between said actuating means and operating device for disengaging them while said actuating means is in en- 40 gagement with said generator, and automatic means normally locking said operating device against movement.

In testimony whereof we have hereunto set our hands and affixed our seals in the 45 presence of the two subscribing witnesses.
